UNITED STATES PATENT OFFICE.

GEORGE BRYANT, OF PHILADELPHIA, PENNSYLVANIA.

LUNCH BOX.

Application filed June 25, 1923. Serial No. 647,697.

To all whom it may concern:

Be it known that I, GEORGE BRYANT, a citizen of the United States, residing at Philadelphia, in the county of Philadelphia and State of Pennsylvania, have invented 5 new and useful Improvements in Lunch Boxes, of which the following is a specification.

This invention relates to lunch boxes and 10 is particularly directed to foldable lunch boxes. One of the principal objects of the present invention is to provide a box of this nature which shall also form a suitable container in which to heat the food and drink 15 which may be stored therein.

Another object of the invention is to provide a lunch box with a suitable heating system.

With these and other objects in view as 20 will be more apparent, the invention consists in certain novel construction and combination and arrangement of parts, the essential features of which are hereinafter fully described, are particularly pointed out 25 in the appended claim, and are illustrated in the accompanying drawing, in which:—

Figure 1 is a vertical sectional view of a lunch box constructed in accordance with my invention.

Figure 2 is a similar view of the device in collapsed condition.

Figure 3 is a perspective view of the lamp per se.

Like characters of reference refer to like 35 parts in all the views.

Referring to the drawing in detail, 10, 11 and 12 represent the upper, intermediate and lower sections of a lunch box, the upper section 10 being provided with a frame 13 40 for holding the smaller receptacles hereinafter described, and being provided with a hingedly mounted cover 14. The bottom section 12 is provided with a floor 15 and with a horizontal partition 16 and between 45 the two there are formed a number of apertures or air vents 17. One side of the portion between the plates 15 and 16 is left open to a sufficient extent to accommodate the fuel tank hereinafter described. The 50 upper portion of the member 12 forms a compartment in which water is placed as shown at 18, which when heated circulates about the receptacles so as to heat up their contents.

55 Slidably mounted in any suitable manner between the plates 15 and 16 is a fuel tank

19 provided at its inner end with a suitable burner 20 and near its outer end with a filling aperture 21 into which the end of a funnel may be introduced so as to fill the 60 tank.

Mounted in the receptacle formed by the three portions 10, 11, 12, are a pair of collapsible containers; each of these containers is made up of a plurality of sections connected in telescoping relation, so as to permit them to be telescoped one within the other for collapsing the containers into a relatively small space. One of the containers which is made up of the sections 22, 23, 24 65 and 25 is preferably rectangular shaped in cross section, while the container made up of the sections 28, 29, 30, and 31 is preferably circular in cross section. The bottom sections 25 and 31 of the containers are seated 70 in the depressed or downwardly curved portions of the base or bottom plate 16, which, together with the frame 13 holds the receptacles in proper place within the boxes.

It will be readily understood that when 80 it is desired to heat the lunch the fuel is ignited at the burner 20, and as the burner heats the water between the two receptacles, the water is placed in circulation about the receptacles and heating of the food is soon 85 effected. After the contents of the receptacles has been disposed of, the box and the receptacles may all be collapsed into a small space so as to be capable of being carried in 90 the pocket.

While I have described what I deem to be the most desirable embodiment of my invention, I do not limit myself to the specific details of construction of material, nor to anything less than the whole of my invention 95 as defined in the appended claim.

What I claim:—

In a device of the class described, a body box comprising a plurality of telescopically connected sections to provide a collapsible 100 body box, a bottom plate supported within the bottom section of said telescopically connected sections, said bottom section provided with air openings therein beneath said bottom plate, said bottom plate provided with 105 depressions, an upper plate supported within said body box, and a plurality of collapsible receptacles supported within said body box by said upper and bottom plates.

In testimony whereof I affix my signature.

GEORGE BRYANT.
